(57) **CLAIM**

The ornamental design for a toothpaste carton, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, front, right perspective view of a first embodiment of a toothpaste carton;
FIG. 2 is a front view thereof;
FIG. 3 is a right side view thereof;
FIG. 4 is a back view thereof;
FIG. 5 is a left side view thereof;
FIG. 6 is a top view thereof; and
FIG. 7 is a bottom view thereof.

FIG. 8 is a top, front, right perspective view of a second embodiment of a toothpaste carton;
FIG. 9 is a front view thereof;
FIG. 10 is a right side view thereof;
FIG. 11 is a back view thereof;
FIG. 12 is a left side view thereof;
FIG. 13 is a top view thereof; and
FIG. 14 is a bottom view thereof.

FIG. 15 is a top, front, right perspective view of a third embodiment of a toothpaste carton;
FIG. 16 is a front view thereof;
FIG. 17 is a right side view thereof;
FIG. 18 is a back view thereof;
FIG. 19 is a left side view thereof;

(Continued)

FIG. 20 is a top view thereof; and
 FIG. 21 is a bottom view thereof.
 FIG. 22 is a top, front, right perspective view of a fourth embodiment of a toothpaste carton;
 FIG. 23 is a front view thereof;
 FIG. 24 is a right side view thereof;
 FIG. 25 is a back view thereof;
 FIG. 26 is a left side view thereof;
 FIG. 27 is a top view thereof; and,
 FIG. 28 is a bottom view thereof.
 The broken lines are shown for the purpose of illustrating parts of the article that form no part of the claim. The dot-dash lines represent the boundaries of the claim and form no part thereof.
